UNITED STATES PATENT OFFICE.

GEORGE E. SHARPE, OF STEUBENVILLE, OHIO.

GAS-HEATER.

1,072,780.

Specification of Letters Patent.

Patented Sept. 9, 1913.

Application filed March 13, 1912. Serial No. 683,572.

To all whom it may concern:

Be it known that I, GEORGE E. SHARPE, a citizen of the United States, residing at Steubenville, in the county of Jefferson and State of Ohio, have invented certain new and useful Improvements in Gas-Heaters, of which the following is a specification.

This invention relates to gas heaters and more particularly to that type of such heaters which are designed to resemble an open fireplace.

It is one aim of the invention to provide a heater of this type so constructed that there will be practically no waste of the heat units generated by the burning fuel and in which the circulation of the heated air currents will serve to draw in the cold air from adjacent the floor in the room in which the heater is positioned and after heating this air deliver it at the top of the heater.

A further aim of the invention is to provide a heater so constructed that while a maximum heating area is afforded, the resistance offered to the passage of the heated products of combustion from the heater will not act to materially retard the draft.

For a full understanding of the invention reference is to be had to the following description and accompanying drawing, in which:—

Figure 1 is a view in front elevation of the heater embodying the present invention. Fig. 2 is a vertical sectional view therethrough on the line 2—2 of Fig. 1. Fig. 3 is a horizontal sectional view on the line 3—3 of Fig. 2. Fig. 4 is a view similar to Fig. 2 illustrating the manner of using a burner of a construction different from that shown in Fig. 2.

Corresponding and like parts are referred to in the following description and indicated in all the views of the accompanying drawing by the same reference characters.

In the drawings, the hollow body of the heater is illustrated as including a back wall 1, side walls 2, and a top 3. The side walls 2 are provided at their forward edges with lateral flanges 4 as is also the top 3 and to these flanges is secured the front of the heater, which front is indicated in general by the numeral 5. The upper portion of the front is in the nature of a hood 6, the for-

ward wall of which is inclined downwardly and outwardly with respect to the remainder of the front so that the lower edge 55 of said wall is spaced from the front to provide an air passage 7. The forward wall of this hood 6 may be either imperforate as shown in the drawings or may be provided with suitably arranged openings, if desired. 60 A front plate 8 formed with openings 9 also constitutes a part of the front 5 of the heater and is positioned in substantially a vertical plane below the hood 6, the lower edge of the forward wall of the hood being 65 spaced forwardly from the upper edge of the said plate 8, as clearly shown in Fig. 2. Below the plate 8 the front of the heater is open as indicated at 10 so as to expose the asbestos covered deflector or back-plate 70 which will be presently described. The lower portion of the front consists of a plate 11 which may be provided with suitably arranged openings 12 and the upper edge of this plate 11 is preferably formed 75 with an inwardly and upwardly inclined flange 12'.

The principles of the invention may be embodied in a heater in which the burner is arranged directly within or upon the deflector or back-plate, which construction is shown in Figs. 1 and 2, or they may be embodied in a heater in which the burner is in the form of a perforated tube, as shown in Fig. 4. 85

In Fig. 2 the numeral 13 indicates the deflector or back-plate, and 14 a gas chamber which is secured to the rear side thereof. A gas supply pipe 15 is secured upon the forward face of the plate 13 and is in communication, by way of an opening 16 formed in the said plate 13 with the interior of the gas chamber 14. The plate 13 is formed with openings 17 through which the gas supplied to the gas chamber 14 may issue in 90 jets and the forward face of the plate 13 is covered with a sheet 18 of asbestos. If desired, a valve such as shown at 19 may be provided for controlling the supply of gas through the supply-pipe 15. A collector for 100 the products of combustion is arranged at the upper end of the deflector plate 13 and comprises a top 20, side walls 21 and a forward wall 22. The top 20 of the collector

extends forwardly from the upper edge of the plate 13, the forward wall 22 of the collector being spaced in front of the said plate and located immediately in rear of the 5 lower portion of the plate 8. The collector extends practically the entire width of the hollow body of the heater and is formed in its top with a number of openings 23. Flues 24 are fitted at their lower ends into 10 the openings 23 and extend vertically therefrom in rear of the plate 8 and have their upper ends fitted in openings 25 formed in the bottom 26 of a chamber which is arranged within the upper end of the body of the 15 heater above the said collector and the deflector plate. This chamber includes in addition to the bottom 26 a forward wall 27, end-walls 28, a top 29 and a rear wall 30, all in spaced relation to the body of the 20 heater. A baffle-plate 31 is arranged within the said chamber in rear of the upper ends of the flues 24 and extends transversely therein with its ends terminating short of the end walls 28 of the chamber, as clearly 25 shown in Fig. 3 of the drawing, and this baffle plate extends from the bottom 26 to the top 29. Air conducting flues 32 are fitted at their lower ends in openings 33 formed in the bottom 26 and at their upper 30 ends are fitted in openings 34 formed in the top 29, these flues providing vertical air 35 passages within the said chamber. A flue 35 opens through the rear wall 30 of the said chamber and extends through the back wall 1 of the heater body.

As before stated, the principles of the invention may be embodied in a heater having a burner of the type shown in Fig. 3 or the burner may be of the type shown in Fig. 4, 40 in which latter instance it consists of a burner-tube 36 having perforations 37 in its upper side, this tube being arranged in advance of the plate 13 and immediately rearwardly of the flange 12' of the plate 11. 45 A gas supply pipe 38 opens into the tube 36.

From the foregoing description of the invention it will be readily understood that the heated products of combustion pass up in front of the plate 13 and into the collector at the upper end of this plate. They are deflected or confined by the forward wall of this collector so as to pass up through the flue 24 and into the chamber above the collector. It will be seen from Fig. 2 of 50 the drawings that they will enter this chamber in advance of the baffle plate 31 and are compelled to pass around the ends of this said plate and into that portion of the chamber located in rear thereof. In this manner 55 the flues 32 are heated and the products of combustion finally pass out through the flue 35.

It will be observed that the lower end of the plate 13 is spaced above the lower end 60 of the body of the heater so that as the air

within the flues 32 becomes heated and ascends, cold air from the vicinity of the floor will be drawn in through the openings 12 and will pass upwardly beneath the lower edge of the plate 13 and between this plate 70 and the rear wall 1 of the heater body. The cold air thus drawn up will pass up through the flues 32 and as the top of the body is closed and escape therefrom can only be had by way of the hood 6, the cold air currents 75 after being heated will pass through the space 7 between the lower portion of this hood 6 and the upper portion of the plate 8, and out into the room in which the heater is located. The air currents immediately adjacent the plate 13 and the collector 20 will pass over the collector and out through the 80 openings 9.

It will be seen from the foregoing that the full benefit of the heat units of the burning 85 fuel is secured and that while the heated products of combustion serve to thoroughly heat the cold air drawn in at the bottom of the heater, they are not materially retarded in their passage from the front of the plate 90 13 to the flue 35.

Having thus described the invention what is claimed as new is:—

1. In a heater of the class described, a casing, a deflector plate, a burner at the 95 front of said plate, a hot-air chamber above said plate, a collector for the products of combustion carried by said plate above the burner, a series of products of combustion flues rising from the collector to said chamber, a series of air flues extending vertically through the said chamber, the product of combustion flues and the air flues being arranged in parallel vertical planes, a baffle plate extending between the two series of 100 flues and terminating short of the ends of each of said series, and an exit products of combustion flue leading from the hot-air chamber in rear of the air flues.

2. In a heater of the class described, a 110 casing having an opening in its front wall, a deflector plate arranged transversely within the casing and opposite the opening in the said forward wall of the same and spaced from the rear wall thereof, a forwardly projecting collector for the products of combustion at the top of the deflector plate, a chamber located above the collector and spaced from the top, back and sides of the casing, a baffle plate extending transversely within the chamber and having its ends spaced from the end walls thereof, a series of flues for products of combustion establishing communication between the top of the collector and the bottom of said chamber, a series of hot-air flues located within the chamber and opening through the top and bottom of the same and communicating with the space between the deflector plate and the rear wall of the casing, said flues 120 125 130

being arranged in vertical parallel planes with the baffle plate, the latter extending between the two series of flues, an exit flue for products of combustion leading from the 5 chamber in rear of the hot-air flues, and a burner located at the lower end of the deflector plate.

In testimony whereof I affix my signature in presence of two witnesses.

GEORGE E. SHARPE. [L. S.]
